UNITED STATES PATENT OFFICE.

FRIEDERICH O. ADAMS, OF PITTSBURG, PENNSYLVANIA.

DESIGN FOR AN INVERTED INCANDESCENT-GAS-LAMP BODY.

No. 40,161.

Specification for Design.

Patented July 20, 1909.

Application filed June 12, 1908. Serial No. 438,232. Term of patent 7 years.

To all whom it may concern:

Be it known that I, FRIEDERICH O. ADAMS, a citizen of the United States, residing at Pittsburg, in the county of Allegheny and State of Pennsylvania, have invented a new, original, and ornamental Design for Inverted Incandescent-Gas-Lamp Bodies, of which the following is a specification, reference being had to the accompanying drawing, forming part thereof.

The figure is a side view of the body portion of an incandescent gas lamp body, showing my new design.

This design comprises at the top a cup-shaped portion with a rounded edge. The cup formation is connected by a rounded portion of less diameter, with a lower dome-shaped portion of like diameter with the cup. The dome-shaped portion is encircled

near the top by a projecting band, and at the bottom its wall turns inwardly and then extends vertically downward and is encircled by a rounded projecting bead. The remaining features of this design consist of a downwardly expanding part having at one side a series of openings with downwardly diverging sides and curved ends. The expanding part terminates in a vertical, downwardly-extending cylindrical wall, encircled by a rounded projecting bead.

I claim:—

The ornamental design for an inverted incandescent gas lamp body, as shown and described.

FRIEDERICH O. ADAMS.
